(57) **CLAIM**

The ornamental design for an automobile console, as shown
and described.

DESCRIPTION

FIG. 1 is a front perspective view of an automobile console
showing my new design;

FIG. 2 is another front perspective view thereof shown on an
enlarged scale;

FIG. 3 is a front elevation thereof;

FIG. 4 is a rear elevation thereof;

FIG. 5 is a right side elevation thereof;

FIG. 6 is a left side elevation thereof;

FIG. 7 is a top plan view thereof; and,

FIG. 8 is a bottom plan view thereof.

The broken lines in the figure descriptions are for illustrative
purposes only and form no part of the claimed design.

1 Claim, 3 Drawing Sheets
